INVENTOR:

John Watson
By his Attorney
William Parker Butler,

UNITED STATES PATENT OFFICE.

JOHN WATSON, OF BROOKLYN, NEW YORK, ASSIGNOR TO EMPIRE MACHINE CORPORATION, A CORPORATION OF NEW JERSEY.

MACHINE FOR JUSTIFYING TYPE.

SPECIFICATION forming part of Letters Patent No. 695,017, dated March 11, 1902.

Application filed June 29, 1901. Serial No. 66,521. (No model.)

To all whom it may concern:

Be it known that I, JOHN WATSON, a citizen of the United States, and a resident of Brooklyn, county of Kings, State of New York, have 5 invented a new and useful Improvement in Machines for Justifying Type, of which the following is a specification.

My invention relates to an improvement in devices for diminishing the impact of the line-holder in its descent when moved by gravity in machines of the character of that described in application for Letters Patent, Serial No. 24,291, filed July 20, 1900, the invention of Frank McClintock, and it relates particularly 10 to devices which act on the line-holder for a limited time only and do not prevent the free movement of the line-holder thereafter on its line of travel through the line.

The invention will be best described by reference to the accompanying sheet of drawings, in which—

Figure 1 is a side elevation of the portion of a justifying-machine to which this improvement is attached, and Fig. 2 is a sectional 25 view on the lines A B of Fig. 1.

Similar letters refer to similar parts throughout the several views.

In the drawings, *f* is the side plate of a type-justifying machine of the character of that referred to in the aforesaid application. *c* is 30 the line-holder. *i* is the top plate. *b* is the upper channel, having a suitable inclination in which the line-holder travels downward by gravity. *e* is the series of space-bars assembled in the line-holder; *z*, the type-characters, also assembled therein. 13 is the opening in the side plate, through which the thinner ends of the space-bars project. These 35 parts are common to all machines of the character shown and described in the application above referred to. In the present construction a second opening 15 in the plate *f* is provided below the opening 13, as shown in Fig. 1, and the line-holder is provided on its face 40 with a longitudinal slot 14, commencing a convenient distance behind the front end of the line-holder and extending to its extreme rear. The slot 14 is cut longitudinally on the face of the line-holder, so as to be opposite the opening 15. Attached to the plate *f* 45 is a bent plate 3, provided with openings 12

and suitable screw 11, which enable it to be shifted upward or downward, as may be desired, and then securely attached thereto. Attached to the upper face of this plate is a 55 lever 1, pivoted at the point 2 and controlled, so far as its forward movement is concerned, by a stop 4 on the plate 3 at its rear end. The front end of the lever 5 is beveled, as shown in Fig. 2, so as to fit into the slot 14 in the 60 line-holder *c* after the device has operated. The backward motion of the lever is controlled by means of a spring passing over a pin 16 on the end of the lever. The other end of the spring abuts against the disk on 65 the screw-pin 10. The tension of the spring may be increased or diminished, as may be desired, by turning the thumb-screw 10.

The method of operation is substantially as follows: Upon the release of the line-holder 70 *c* by the operator after filling it moves down the track or way *b* by the action of the force of gravity, necessarily with increasing momentum. As soon as it reaches the projecting end 5 of the lever 1 it forces the end of 75 the lever to the right, compressing the spring 16. Thereupon the friction existing between the end of the lever 5 and the side of the line-holder at the point 17 retards the downward movement. When the full portion 17 of the 80 line-holder *c* has passed the end of the lever, the latter is thrown forward into the slot 14 by means of the spring 9, and thereafter it ceases to perform any function and leaves the line-holder entirely free to continue its 85 travel down the inclined track *b* by the action of gravity. The tension of the spring is adjustable and may be made such as to retard the movement of the line-holder sufficiently to make the operation satisfactory. 90

I claim as my invention—

1. The combination of a line-holder arranged to descend by gravity, and a device for diminishing the impact of the line-holder and retarding its movement substantially as 95 described.

2. The combination of a line-holder arranged to descend by gravity, a side plate against which it slides; and a device on the side plate for diminishing the impact of the 100 line-holder and retarding its movement substantially as described.

3. The combination of a line-holder arranged to descend by gravity, a side plate against which it slides; and a lever arranged to engage with the line-holder and retard its movement, and devices substantially as described for controlling the movement of the said lever.

4. The combination of a line-holder arranged to descend by gravity, a side plate against which it slides, and a lever pivoted on the side plate arranged to engage with the line-holder and retard its movement and devices substantially as described for controlling the movement of the said lever.

5. The combination of a line-holder provided with a slot of suitable length upon its inner face, a side plate against which it slides; and a lever pivoted upon the side plate of the machine, the forward end of which is arranged to engage with and retard the movement of the line-holder as it descends, and devices substantially as described whereby after the forward end of the line-holder has

passed the point of the lever, the point is forced forward into the slot and ceases to operate. 25

6. The combination of a line-holder provided with a slot of suitable length on its inner face; a side plate against which the line-holder slides; a lever pivoted upon the side plate of the machine, the forward end of which is arranged to engage with and retard the movement of the line-holder as it descends; a stop upon the plate for limiting the forward motion of the lever; and a spring 30 35 the tension of which may be regulated by a suitable thumb - screw for controlling the movement of the said lever.

In testimony that I claim the foregoing as my invention I have signed my name, in presence of two witnesses, this 28th day of June, 1901. 40

JOHN WATSON.
